UNITED STATES PATENT OFFICE.

NATHANIEL G. BALDWIN, OF WASHINGTON, PENNSYLVANIA.

BOTTLE-STOPPER.

SPECIFICATION forming part of Letters Patent No. 656,689, dated August 28, 1900.

Application filed February 7, 1900. Serial No. 4,385. (No model.)

To all whom it may concern:

Be it known that I, NATHANIEL G. BALDWIN, a citizen of the United States, residing at Washington, in the county of Washington 5 and State of Pennsylvania, have invented a new and useful Bottle-Stopper, of which the following is a specification.

This invention relates to bottle-stoppers, and has for its object to provide improved 10 means for preventing the refilling of the bottle. It is also designed to provide for the convenient insertion of the stopper into the bottle-neck and to prevent withdrawal thereof without damaging the stopper, and thereby 15 indicating that the bottle has been previously opened, while at the same time facilitating the pouring out of the liquid contents of the bottle.

With these and other objects in view the 20 present invention consists in the combination and arrangement of parts, as will be herein-after more fully described, shown in the accompanying drawings, and particularly pointed out in the appended claims, it being understood 25 that changes in the form, proportion, size, and minor details may be made within the scope of the claims without departing from the spirit or sacrificing any of the advantages of the invention.

30 In the drawings, Figure 1 is a sectional elevation of the neck portion of the bottle having the improved stopper applied thereto. Fig. 2 is a transverse sectional view taken on the line 2 2 of Fig. 1. Fig. 3 is a similar 35 view taken on the line 3 3 of Fig. 1.

Corresponding parts in the several figures of the drawings are designated by like characters of reference.

Referring to the accompanying drawings, 40 1 designates the body of any ordinary bottle, having the usual neck 2, which is provided at its lower end with a valve-seat 3, having inwardly-convergent walls and designed to loosely support a conical valve 4, preferably 45 formed of glass. The engaging walls of the valve and the valve-seat are preferably ground, so as to provide an air-tight closure for the neck when the bottle is in its usual upright position.

50 Located above the valve is a protector therefor, comprising opposite longitudinal plug-sections 5 and 6. As indicated in Figs.

2 and 3 of the drawings, these plug-sections are substantially semicircular in cross-section, so as to fit snugly the interior walls of 55 the neck. The plug-section 6 is the first to be inserted in the bottle-neck and is provided at its lower end with a lateral foot or extension 7, which has a notch or perforation 8 formed in its outer end. Extending longitudinally of the inner flat face of the plug-section is a semicircular groove 9, which terminates immediately above the foot 7 and is provided at its lower end with an enlargement 10, so as to form an upwardly and inwardly inclined shoulder 11, which overhangs 60 the enlarged portion of the groove. The other plug-section 5 is provided with a head 12, which rests upon the upper end of the plug-section 6 and is provided with an opening or perforation 13, aligned with the upper 65 end of the groove 9 in the other plug-section. As indicated in Fig. 1 of the drawings, the section 5 terminates short of the foot 7, so as to provide a space 14, communicating between 70 the notch or opening 8 and the groove 9. Adjacent to the lower end of the plug-section 5 there is provided a transverse slot 15, which 75 extends entirely through the section and communicates with the groove 9. 80

To prevent withdrawal of the plug-section 5, there is provided a glass pin 16, which is received within the slot 15 and projects at its inner end into the enlarged portion of the groove 9, while the opposite end of the pin is 85 received within a socket 17, formed in the adjacent wall of the bottle-neck.

In assembling the plug-sections the section 6 is first introduced into the bottle-neck, so that the foot 7 may be spaced a suitable distance above the valve 4. The plug-section 5 is then inserted, with the inner end of the pin 16 inclined downwardly through the slot 15 and received within the groove 9, so that the outer end of the pin may not bind upon the 90 adjacent wall of the bottle-neck. When the head 12 engages the upper end of the section 6, the outer end of the pin 16 will be received in the socket 17. In this position of the plug-sections the inner end of the pin will be in engagement with the adjacent wall of the section 6, so as to prevent accidental displacement of the opposite end of the pin from the socket in the bottle-neck. Outward move- 95 100

ment of the section 5 is prevented by reason of the pin being received within the socket 17, and should there be any looseness of the plug and the pin the inner end of the latter would 5 engage the overhanging wall 11 and be forced thereby tightly into the socket, so as to prevent a complete withdrawal of the plug. It will now be apparent that the head of the section 10 5 overhangs the outer end of the section 10 6, so as to prevent access to the latter, whereby it might be moved to disengage the shoulder 11 from the pin, and thus permit an entire withdrawal of the protector.

To pour out the liquid contents of the bottle, the latter is inverted, as usual, so as to unseat the valve 4, whereby the liquid contents 15 may pass outwardly through the valve-seat, the notch 8, the passage 14, the groove 9, and the opening 13 in the head of the plug without disturbing any of the parts of the plug. Any attempt to fill the bottle will result in a sealing of the valve, and thereby effectually 20 prevent liquid from being introduced into the bottle. It is preferable to employ a cork or 25 supplemental stopper 18 in the outer end of the bottle-neck, so as to normally close the opening 13 and prevent ingress of foreign matter into the groove 9, which would result in a stoppage of said groove.

30 It will be noted that the outer end of the pin 16 is provided with an enlarged and weighted head 19, which is designed to effect a quick and positive seating of the head within the socket 17 and also to normally maintain the pin in engagement with said socket.

35 What is claimed is—

1. The combination with a bottle, having a valve-seat in the neck thereof, of a valve loosely seated upon the valve-seat, a sectional 40 protecting-plug received within the neck, and a locking device engaging both plug-sections and also having an interlocked connection with the neck of the bottle.

2. The combination with a bottle, having a 45 valve-seat in the neck thereof, of a valve loosely seated therein, a sectional protecting-plug received within the neck, and a locking-pin engaging both plug-sections and also received within a socket formed in the bottle-neck.

3. The combination with a bottle, having a valve-seat in the neck thereof, and a valve loosely seated therein, of a sectional protecting-plug, one of the sections having a longitudinal groove, and the other section having a transverse slot, and a locking-pin extending transversely through the slot, having 55 one end received within the groove of the other section, and its opposite end received 60 within a socket formed in the bottle-neck.

4. The combination with a bottle, having a valve-seat in the neck thereof, and a valve loosely seated therein, of a sectional protecting-plug, one of the plug-sections having 65 a longitudinal groove, provided with an enlargement, the other plug-section having

a transverse slot communicating with the groove, and a locking-pin extending in opposite directions through the slot, the inner end of the pin being received within the enlargement 70 of the groove, and the opposite outer end being received within a socket formed in the bottle-neck.

5. The combination with a bottle, having a valve-seat formed in the neck thereof, and a valve loosely mounted upon the valve-seat, of a protecting-plug, comprising longitudinal sections, one of the latter having a longitudinal groove in its inner face, and the other section having a head overlapping the outer 80 end of the former section, and having an opening aligned with the outer end of the groove.

6. The combination with a bottle, having a valve-seat formed in the neck thereof, and a valve loosely mounted in said seat, of a protecting-plug, comprising longitudinal sections, one of the latter having a transverse foot at its inner end, said foot being provided with an opening or perforation, and the inner 90 face of the section having a longitudinal groove, the other section having a transverse head resting upon the outer end of the former section, and also terminating short of the foot thereof, the head having an opening or 95 perforation aligned with the outer end of the groove.

7. The combination with a bottle, having a valve-seat formed in the neck thereof, and a valve loosely fitting said seat, of a protecting-plug, comprising a pair of longitudinal sections, one section having a longitudinal groove formed in its inner face and provided with an enlargement at its lower end, and a lateral foot provided with a perforation or opening, 100 the other section having a lateral head resting upon the outer end of the former section, said head having an opening aligned with the outer end of the groove, and said section also having a transverse slot communicating with 105 the enlarged portion in the groove, and a locking-pin extending in opposite directions through the slot, the inner end of the pin being received within the enlargement of the groove, and the outer end of the pin being 110 received within a socket formed in the bottle-neck.

8. The combination with a bottle, having a valve-seat in the neck thereof, of a valve for the valve-seat, a sectional protecting-plug, 115 and a weighted locking-pin engaging both sections of the plug, the weighted end of the pin being seated within a socket formed in the bottle-neck.

In testimony that I claim the foregoing as 120 my own I have hereto affixed my signature in the presence of two witnesses.

NATHANIEL G. BALDWIN.
